2 Claims. (Cl. 24—140)

This invention relates to a method of lacing and to the product obtained thereby, and has as its main object and feature the provision of a lacing more economical of space and neater in 5 appearance than the well-known criss-cross method of double lacing.

In the accompanying drawing the invention is shown in elevation in a concrete and preferred form with the lacing applied to two adjacent sections or panels of a corset.

1 and 3 indicate two adjacent but spaced-apart sections of a corset. Adjacent the two longitudinal edges 1a and 3a of said sections, are arranged two opposed rows of eyes 1a' and 3a', 10 the eyes of each row being in fixed relation to each other. One end of the strand or lace 5 is inserted in one of the uppermost eyes 1a' and the strand drawn through the eye almost its entire length, leaving enough projecting beyond 15 the eye to admit of tying or otherwise fastening; strand 5 is then drawn in horizontal direction across to and threaded into and through the opposite eye of the series 3a' and drawn back in reverse horizontal direction and threaded 20 again into the first-mentioned eye of the series 1a'; and then drawn downwardly, as here illustrated, and threaded into the next eye below of the 1a' series of the eyes, then again horizontally across to and through the opposite eye of the 3a' 25 series, and then back to and again through the second-mentioned eye of the 1a' series, and so on until the desired length has been laced. One end of the strand will then be projecting at the beginning of the lacing and the other end, which 30 has been used for threading, at the termination of the lacing and these ends may be fastened in any suitable manner, by tying, as shown in the drawing, or otherwise. As here illustrated, eyes have been employed to engage strand 5 but loops, 35 eyelets or apertures, or any other suitable device, may be used. It is, however, preferable to use

a device that projects beyond the edges of the parts to be laced together such as eyes or loops, rather than apertures or eyelets, because, there being no overlapping by the strand of the parts to be laced together, as there must be when eyelets or apertures are used, a flatter and neater appearance is produced with the lacing all on one side of the garment. This lacing may, of course, be employed for other uses than that shown here.

It will be noted that, after threading has been effected, the lacing may be tightened or loosened.

This application is a division of one filed July 29, 1933, Ser. No. 682,744.

I claim:

1. The method of threading a single strand through two opposed rows of eyes, the eyes of each row being in fixed relation to each other, which consists in threading one end of the strand through an eye in one row, then through the 20 opposite eye in the other row, then again through the first-mentioned eye and then through the next eye in the same row, and in repeating this operation until the desired length has been threaded.

2. As an article of manufacture, a lacing for joining two parts together, devoid of the usual diagonal criss-crossing of strands, comprising a single strand and two opposed rows of eyes for engagement therewith, arranged respectively 30 along the outer edges of the parts to be joined, the eyes of each row being in fixed relation to each other, and said strand stretching across the two opposed rows in horizontal direction and being in engagement once with the eyes of one row 35 and twice with the eyes of the other row and overlapped upon itself in the horizontal direction and progressing in longitudinal direction along one of said rows of eyes.

ROBERT T. ALLIS.
